UNITED STATES PATENT OFFICE.

CLARENCE R. GILLETT, OF CHICAGO, ILLINOIS, ASSIGNOR TO THE MAGIC
LIGHT COMPANY, OF SAME PLACE.

DESIGN FOR A LAMP-FIXTURE.

SPECIFICATION forming part of Design No. 30,621, dated April 25, 1899.

Application filed March 24, 1899. Serial No. 710,370. Term of patent 7 years.

To all whom it may concern:

Be it known that I, CLARENCE R. GILLETT, a resident of Chicago, in the county of Cook and State of Illinois, have invented and produced a new and original Design for Lamp-Fixtures, of which the following is a specification, reference being had to the accompanying drawing, forming a part thereof.

The drawing is a view in side elevation of the lamp-fixture embodying my design.

As shown in the drawing, the leading or most characteristic feature of my design consists in a lamp-fixture comprising the outwardly and inwardly curved or bow-shaped side bars A and A', from which depend the vertical bars B and B', the lower ends of which are shown as extending toward each other and as meeting in a coupling C. The space circumscribed by the bars B B' is of less width than the space bounded by the upper curved bars A A'. From the lower ends of the bars A A' project, respectively, the tubular parts E and E'. As shown, the bars A and A' are united to a coupling G at the lower end of a rod H, the upper end of this rod H being shown as provided with a hook h, and the

body of the rod being shown as formed with spiral corrugations. A cylindrical reservoir K is shown as mounted upon the rod H, and from this reservoir the supply of liquid fuel will be delivered to the lamp. A regulating-valve is placed at the lower end of the rod A, the stem of this valve having connected thereto a hand-wheel P.

Gasolene or like liquid fuel from the reservoir K will pass downward through the tubular rod H, thence through the tubular bar A and through the tubular rod E, and passing from the jet at the end of the rod E to be drawn into the expanded end of the tubular rod E', and will pass thence down the side bar B' to the coupling C.

Having described my invention, what I claim as new, and desire to secure by Letters Patent, is—

The design for a lamp-fixture substantially as herein shown and described.

CLARENCE R. GILLETT.
